US00D998470S

(12) **United States Design Patent** (10) Patent No.: **US D998,470 S**
Gruzelier et al. (45) Date of Patent: **** Sep. 12, 2023**

(54) **BOTTLE**

- (71) Applicant: **The Procter & Gamble Company**, Cincinnati, OH (US)
- (72) Inventors: **Julian Richard John Gruzelier**, Vaud (CH); **Gillian Meredith Anne Haro**, Amsterdam (NL); **Brett Tom**, Richmond, CA (US); **Wei Gu**, Singapore (SG); **Reid Andersen**, Schleggel, Brooklyn, NY (US); **Danvu Nam Nguyen**, San Francisco, CA (US); **Calvin Shenghuai Lin**, Singapore (SG); **Longfei Zhang**, Singapore (SG)
- (73) Assignee: **The Procter & Gamble Company**, Cincinnati, OH (US)
- (**) Term: **15 Years**
- (21) Appl. No.: **29/861,937**
- (22) Filed: **Dec. 5, 2022**

FIG. 17 is a front perspective view of a third embodiment of a bottle, embodying our new design;

FIG. 18 is a back perspective view thereof;

FIG. 19 is a front view thereof;

FIG. 20 is a back view thereof;

FIG. 21 is a first side view thereof;

FIG. 22 is a second side view thereof;

FIG. 23 is a top view thereof; and

FIG. 24 is a bottom view thereof;

FIG. 25 is a front perspective view of a fourth embodiment of a bottle, embodying our new design;

FIG. 26 is a back perspective view thereof;

FIG. 27 is a front view thereof;

FIG. 28 is a back view thereof;

FIG. 29 is a first side view thereof;

FIG. 30 is a second side view thereof;

FIG. 31 is a top view thereof; and,

FIG. 32 is a bottom view thereof.

The broken lines shown in the drawings depict portions of the bottle that form no part of the claimed design.
